Specification for Design.

Patented July 9, 1907.

Application filed May 23, 1907. Serial No. 375,365. Term of patent 7 years.

To all whom it may concern:

Be it known that I, WILLIAM MILLARD, a subject of the King of the United Kingdom of Great Britain and Ireland, residing at the borough of Manhattan, in the city, county, and State of New York, have invented a certain new, original, and ornamental Design for Mounts for Fluid-Vending Machines, of which the following is a specification, reference being had to the accompanying drawings, which form a part thereof.

The drawing is a perspective view of a mount for a fluid vending machine, showing my new design.

What I claim is:

The ornamental design for a mount for a fluid vending machine as shown.

WILLIAM MILLARD.
